US00D912099S

(12) **United States Design Patent** (10) Patent No.: **US D912,099 S**
Manna et al. (45) Date of Patent: **** Mar. 2, 2021**

(54) **TRAVELING MACHINE FOR POWER SHOVELS**

(71) Applicant: **Caterpillar SARL**, Geneva (CH)

(72) Inventors: **Niladri Manna**, Hyogo (JP);
Kazumasa Matsumura, Hyogo (JP);
Ayaka Nagai, Hyogo (JP); **Junji Mizugaki**, Hyogo (JP)

(73) Assignee: **Caterpillar SARL**, Geneva (CH)

(**) Term: **15 Years**

(21) Appl. No.: **29/717,789**

(22) Filed: **Dec. 19, 2019**

(30) **Foreign Application Priority Data**

Jun. 26, 2019 (JP) 2019-014147

(51) **LOC (13) Cl.** **15-03**

FOREIGN PATENT DOCUMENTS

JP 1580238 7/2017

Primary Examiner — Mark A Goodwin

(57) **CLAIM**

The ornamental design for a traveling machine for power shovels as, shown and described.

DESCRIPTION

FIG. 1 is a front, left perspective view of a traveling machine for power shovels showing our new design;

FIG. 2 is a front, right perspective view thereof;

FIG. 3 is a rear, left perspective view thereof;

FIG. 4 is a rear, right perspective view thereof;

FIG. 5 is a front view thereof;

FIG. 6 is a rear view thereof;

FIG. 7 is a left side view thereof;

FIG. 8 is a right side view thereof; and,

FIG. 9 is a top view thereof.

1 Claim, 9 Drawing Sheets
